UNITED STATES PATENT OFFICE.

HANS P. RASMUSSEN, OF KENT, WASHINGTON.

COMBINED AUTO BED AND LUGGAGE CARRIER.

Application filed September 29, 1924. Serial No. 740,510.

My invention relates to an improvement in equipment particularly designed for attachment to automobiles to facilitate camping, and has for its particular object the provision of a combined luggage carrier, table, and bed.

It is a considerable problem so to arrange a camping outfit that it is convenient of access when required, but so that it is least conspicuous and in the way when traveling. It is undesirable to clutter the running boards with luggage, for ingress and egress is thereby blocked, but with the ordinary type of luggage carriers a small bundle only can be supported thereon. While many cars are formed with beds which may be made up within the car, yet it is often desirable to make up a separate bed without the car. My invention is particularly designed to accomplish these several objects, and in addition, to provide a satisfactory table in association with and conveniently placed in relation to a grub box.

A further object is the provision of a device of this character which will enable luggage to be assembled and rolled into convenient bundles and which may thereafter be folded without disturbing the bundles, and in such a way as to maintain them in position for traveling.

A further object is the provision in connection with such a device, of means which will serve in the dual capacity of a brace and leg for the projecting end of the bed.

It is also my object to provide a device of the character described which will be simple, cheaply constructed, and easy to fold or unfold, and therefore convenient in use.

My invention comprises those novel parts and combinations thereof which are shown in the accompanying drawings, described in the specification and particularly defined by the claims terminating the same.

In the accompanying drawings I have shown my invention in the form which is now preferred by me.

Figure 1 is a side elevation of the device, shown folded and attached to the rear end of the automobile.

Figure 2 is a similar elevation showing the device unfolded and with the bed set up.

Figure 3 is a plan view of the device unfolded, a part being broken away.

Two members, which may be frames of any suitable construction, and which for convenience I have termed platform mem-

bers, are hinged together. One of these platform members 1 is provided with means such as the extensions 10 and U-bolts 11 by means of which it may be secured to a frame member C of an automobile. The other platform member 2 is hinged at 21 to the platform member 1 and when unfolded as shown in Figure 2, lies in a common plane with the member 1. From this position it is adapted to swing into a position, as shown in Figure 1, substantially at right angles to the platform member 1.

The two platform members may conveniently be formed of angle irons forming the sides thereof and connected by suitable transverse members. A grub box 13, resting at its ends upon the flanges of these angle bars, or otherwise supported therefrom, may form the transverse member of the platform member 1 and the side angle of the platform member 2 may be connected by slats or similar members 22, preferably in contact or closely adjacent each other, which when the device is unfolded conveniently serves as a table. In addition cross bars 23 and 33 may be employed to connect the side angles or the brackets 3 and 30 forming part thereof or attached thereto, as will be explained hereinafter. The grub box being supported upon the platform member 1, and the slats 22 forming the table being supported upon the adjacent member 2, it will be apparent that when the table is in horizontal position the grub box will be immediately accessible and adjacent thereto.

Brackets 3 are supported upon the swinging ends of the members 2 at each side thereof, and preferably extend upwardly and rearwardly therefrom. These are shown as comprising simply metal straps. Rearwardly facing slots 31 are formed in these brackets 3, which slots are intended to receive a transverse bar 41 secured in the end of a bed fabric 4. If desired springs 40 may be interposed between the end of the bed fabric and the transverse bar 41. Similar brackets 30 are secured to the platform member 1 or are otherwise supported from the frame member C of the automobile. These likewise have forwardly facing slots 32 formed therein, which are intended for the reception of a bar 42 secured to the end of the bed fabric 4 opposite to the bar 41.

The length of the bed fabric 4 is made such or is adjusted to be of such length that it will be tightly stretched between the bars

41 and 42 when the latter are positioned in their respective slots 31 and 32. In order to position the bars within these slots, therefore, the platform member 2 must not have 5 been swung fully down but must be raised somewhat to bring its bracket 3 upward and forward. By then permitting it to swing downward so that the platform members 1 and 2 lie in a common plane, the bed fabric 10 4 is stretched tightly and the bars 41 and 42 are secured in their slots to prevent accidental removal thereof. A latch 5 extending between the members 1 and 2 below the pivot 21, serves to prevent the breaking of 15 the joint at this point and prevents accidental collapse of the bed. The tension of the fabric 4 may be regulated, if desired, by forming the bar 42 of non-circular cross section, at least where it is received in the 20 slots 32, and by wrapping the fabric thereabout, so that by wrapping more fabric about this bar 42 the tension of the fabric when the bed is set up may be increased, or vice versa. 25 A brace 6 is employed to maintain the device in folded position. This is preferably made of such length and is so positioned that when the device is unfolded it will reach to the ground and serve as a leg to 30 support the outer end of the bed, or to support the table. It may conveniently be pivoted upon the member 2 at 20 and is provided with a slot 61 which engages over a pin 31 upon the member 1, to prevent accidental unfolding of the device when traveling. This tendency is also resisted by pressure of the luggage against the upraised member 2, which will tend to prevent disengagement of the slot 61 from its bar 33. 35 It will be evident that the leg 6, resting upon the ground when the device is unfolded, will tend to force upward the swinging end of the member 2 and will tend to break the joint at the hinge 21. This is particularly true by reason of a tendency of the 40 platform member 1 to give with the spring S of the car. For this reason, also, it is essential that some means be provided, such as the latch 5, for preventing breaking of the device at the hinge joint 21. The member 6, when acting as a brace, is positioned 45 so that it will extend substantially from the upper edge of the luggage carrier to its inside lower edge, thus extending across the space which would be occupied by rolls. By making the rolls of a length to lie between the two braces 6, they are thus held more securely in position, without lashing. 50 The device when in position to function as a luggage carrier is of considerable length and capacity. All articles may be made up into a single large roll while the bed is still set up, and may then be left in position, merely folding up the member 2 and securing 55 the braces 6, whereupon the device and

the luggage supported thereby is in position for travel without further stowing away or securing it. This will considerably facilitate making and breaking of camp and maintains all loose articles in a single roll 70 upon the rear of the car and out of the way.

What I claim as my invention is:

1. In a combined luggage carrier and bed frame for automobiles, a hingedly connected two part frame adapted to receive a bedding-supporting web, one part of said frame being provided with means for fixedly securing it to the rear end of an automobile to occupy a horizontal plane, the other part of the frame being adapted to swing upon the other part between horizontal and vertical planes, means for securing said swinging part in either of said positions, the swinging part of the frame having luggage retaining members extending between its sides, and a storage box fitting in the fixed frame part and adapted to serve as a luggage carrying floor for said frame section. 80

2. In a combined luggage carrier and bed frame for automobiles, a bed frame composed of two sections hinged together to fold into right angular and aligned positions, one of said frames at the edge opposite to said hinge being provided with an arm and means for clamping it to the chassis side frame at the rear, to occupy a horizontal position, said section being adapted to receive a storage box to serve as a support for the bedding, combined leg and brace bars secured to the swinging bed frame section and means for detachably securing said brace bars to the fixed bed frame section to thereby support the swinging section in raised position and to act as luggage retaining bars. 90

3. In a combined luggage carrier and bed frame for automobiles, a hingedly connected two part bed frame, said parts being adapted to swing into aligned and right angular positions, one part of said frame being provided with means for securing it to the chassis side bars, a storage box adapted to fit in and be carried by said fixed frame section and to serve as a luggage retaining floor therefor, the other frame section having luggage retaining members filling the opening therein, combined supporting legs and connecting braces pivoted to said swinging section, said braces and the fixed frame section having engaging members by which the swinging frame may be held in raised position, the bed frame sections having upwardly extending arms provided with means for securing a bedding supporting web, and a bedding supporting web adapted to be detachably secured to said arms. 110

Signed at Kent, King County, Washington, this 23rd day of September, 1924.

HANS P. RASMUSSEN.
